UNITED STATES PATENT OFFICE.

JOHN HENRY MERSHON, OF VAN ALSTYNE, TEXAS.

DRY-CLOSET COMMODE.

1,071,073.

Specification of Letters Patent.

Patented Aug. 26, 1913.

Application filed February 16, 1911. Serial No. 609,022.

To all whom it may concern:

Be it known that I, JOHN HENRY MERSHON, a citizen of the United States, residing at Van Alstyne, in the county of Grayson and State of Texas, have invented certain new and useful Improvements in Dry-Closet Commodes, of which the following is a specification.

My invention relates to new and useful improvements in dry closet commodes. Its object is to provide a sanitary dry closet for places not having the facility of a sewerage or water works system.

A further object is to provide a device of the character described that will be readily cleaned, simple in construction, practically odorless, and adapted to be emptied with facility.

With these and various other objects in view, my invention has relation to certain novel features of the construction, an example of which is illustrated in the accompanying drawing.

In the drawing is shown a sectional elevation with parts thereof broken away, and with letters applied to the various parts of the structure, which letters are referred to hereinafter.

The closet A, which is provided with a door B has beneath it a rectangular aperture or cavity C extending from beneath the middle portion of the closet some distance beyond the rear wall thereof. A casing D preferably of sheet metal is made stationary in the aperture C beneath the closet. This casing has no bottom, nor rear wall, and has its top level with the closet floor. An aperture is provided in said top, which is encircled by a flange E. Upon this flange is mounted a stool F, approximately cylindri-

cal in shape, and having a rim G upon its upper extremity, which forms a seat. A hinged lid H is used in conjunction with the seat G in the usual manner. A receptacle J is mounted in the cavity C beneath the closet, 45 and is ordinarily positioned within the casing D below the aperture in the top of said casing. In order to empty said receptacle, however, it may be readily withdrawn from the casing into the exterior portion of the 50 cavity C. A small flanged aperture L is provided in the top of the casing D, which communicates with a ventilating flue K, which extends upwardly through the roof of the closet. This flue serves to carry off any 55 foul gases and prevents the air of the closet becoming contaminated.

The above described device is especially adapted for use in rural districts, villages, railway stations, or any other places not provided with sewerage systems. 60

What I claim is:

In a closet, the combination of a metal casing having its bottom and side open, said casing having two openings in its top, 65 flanges formed integral with the top and directed upwardly thereupon, said flanges each surrounding one of the openings, a cylindrical stool snugly receiving one of the flanges and having a closure at its upper end, 70 a vent pipe snugly receiving the other flange in its lower end, and a receptacle fitting in the casing.

In testimony whereof I have signed my name to this specification in the presence of 75 two subscribing witnesses.

JOHN HENRY MERSHON.

Witnesses:

J. M. McLEMORE,
J. H. ELLIOTT.
